PENNSYLVANIA, A CORPORATION OF VIRGINIA.

MOLD FOR PRINTERS' STRIP MATERIAL.

1,283,626.

Specification of Letters Patent.

Patented Nov. 5, 1918.

Application filed July 13, 1917. Serial No. 180,395.

To all whom it may concern:

Be it known that we, JOHN SELLERS BANCROFT and AMOS L. KNIGHT, both citizens of the United States, and residents of Philadelphia, county of Philadelphia, State of Pennsylvania, have invented certain new and useful Improvements in Molds for Printers' Strip Material; and we do hereby declare the following to be a full, clear, and exact description of the same, reference being had to the accompanying drawings, forming part of this specification, and to the characters of reference marked thereon.

The invention relates to mold apparatus for elements of printing forms, particularly to molds of the type disclosed, for example, in United States Letters-Patent No. 1,222,415, dated April 10th, 1917. Molds of this type are adapted as part of a type casting machine to produce printers' strip material, such as rules, leads, and like elements of a printing form in fused sections to form strips of indefinite length or in non-fused sections of predetermined length.

The patented apparatus, generally speaking, comprises a mold having an opening for the entrance of molten metal and being open at one end for the exit of the congealed metal, means for feeding forwardly the congealed metal and means for forcing molten metal behind the forwardly fed congealed metal. The operations of casting and feeding are carried on in timed relation to each other and are repeated in accordance with the amount of product desired. For feeding the congealed metal a reciprocatory mold blade is shown in the said patent, which blade advances, when the metal in the mold cavity is congealed, to push said metal forwardly toward the exit opening of the mold, and retreats thereafter to leave a cavity for the reception of the molten metal to form the succeeding cast.

In casting type metal strip material having a printing surface, a matrix formed to produce such surface is used, while in the case of non-printing material it is usual to employ a blank matrix. The main object of the present invention is to provide a matrix composed of a plurality of exchangeable parts, the upper member or part being provided with a recess to form the face or equivalent portion of the element to be cast and the lower member being provided

with a slot or the like, adapted to be positioned in alinement with the recess of the upper member, and forming that portion of the element between the portions formed by the upper matrix member and the mold proper. A simple exchange of one or both of the matrix members thus makes it possible with the same mold parts to produce strip elements of varying formation. For example, a matrix adapted to give a beveled formation, such as to facilitate the insertion of slugs, type and the like in a printing form may be altered by exchanging its lower member merely, so as to produce an element having a shouldered formation such as is particularly advantageous in the case of rules for a form from which electrotypes are to be made. Other advantages and other objects of our invention will appear in connection with the following description of the embodiment thereof shown in the accompanying drawings in which—

Figure 1 is a sectional view of a mold, the section being substantially in the plane of the mold blade,

Fig. 2 is a cross section of the mold, the section passing through the nozzle opening and also through parts of the pressure screw clamping device,

Fig. 3 is a perspective view of the lower matrix member,

Fig. 4 is a cross section of the two part matrix shown in Figs. 1 and 2, whereby a shouldered rule is produced and

Fig. 5 is a cross section of a matrix having a modified lower member whereby a beveled rule is produced.

Like reference characters in the several figures indicate the same parts.

Inasmuch as apparatus substantially corresponding to that of the patent hereinbefore mentioned has gone into extensive public use and is well understood in the art, it is thought to be unnecessary to illustrate herein operating mechanism or stops for the mold blade and means whereby the molten metal is injected into the mold cavity, nor is it necessary, for an understanding of the present improvement, to illustrate in detail means for severing the gate from the side of the strip, especially as operating mechanism and the metal melting and injecting mechanism may substantially correspond to mechanism found in the type casting machines manu-

factured by the Lanston Monotype Machine Company, which have been in extensive public use for many years.

Referring to the accompanying drawings, it will be seen that the mold illustrated in Figs. 1 and 2 embodies a mold base block 3, which is formed with a channel therethrough in the direction of movement of the mold blade, thus providing front and rear upwardly extending portions 4 which are adapted to be connected across the top of the mold by a tie bar or bars 5. Confined within the channel extending through the mold base are the type or side blocks between which the cavity for the reception of the molten metal is formed, and these type or side blocks are preferably in the form of bars which extend beyond the mold cavity in each direction and are adapted to be separated a distance which will determine the width of the mold cavity and consequently the point size of the element being cast. The rear type or side block 8 (Fig. 2) is preferably formed with a smooth inner face and constitutes one wall of the mold cavity as well as the wall of the passage in which the mold blade works and of the exit opening in which the congealed metal is retained during the injection of molten metal to form a succeeding cast. The front type or side block may be of similar construction and arranged to be placed in opposition to the block 8 but it is preferably formed in two sections 9 and 10, for convenience of manufacture, inasmuch as it has been found desirable to provide at one side of the mold cavity a channel and exit opening through which air and a portion of the molten metal from the mold cavity may escape in the form of a more or less spongy mass, which, for convenience, may be called a gate lying at one side of the element and adapted to be severed therefrom.

By reference to Fig. 2 it will be seen that between the two sections 9 and 10 there is formed a narrow space which widens out within the type block in the form of a channel which is conveniently of a dove-tail or triangular cross section, as indicated at 12. The channel 12 and the narrow entrance slot which connects the channel with the mold cavity are preferably slightly tapered or of increasing cross section toward the exit end so as to prevent binding during the movement of the gate toward the exit of the channel. Where the front type block is made in two sections, as just described, the upper section 9 is preferably made rigid with the lower section 10 by being fixed accurately thereto and supported by an upwardly extending portion 10^a of the section 10, to which it is connected by screws or other suitable fastenings, as shown clearly in Fig. 2.

The two type blocks forming between them the mold cavity and mold blade channel are

positioned laterally of the mold base by a packing plate 17 placed back of the rear type block and by the pressure screw 18 passing through the front projection 4 of the mold base and adapted to operate against the front type block. This pressure screw, in the preferred construction, is operated periodically in time with the feeding of the element being cast so as to clamp the walls of the mold cavity together during the casting operation and to release such pressure during the feed of the element forwardly in the mold cavity.

The bottom of the mold cavity is formed by the mold base and is provided with a nozzle opening 20 through which the molten metal is injected into the mold cavity through a nozzle 20^a indicated in dotted lines in Fig. 1.

In the specific embodiment of the invention illustrated herein the mold is adapted for the making of printers' type high strip material provided with a printing surface, the latter and the portion of the strip in proximity to said surface being formed by the upper matrix member 21 provided in its lower face with a recess 22 but it will be understood that one or more recesses or other configuration may be formed in the matrix depending upon the character of the face desired.

The upper matrix member 21 which as shown is provided with a single V shaped groove, being designed to make a printers' rule, with a single, narrow printing edge, rests upon the lower matrix member 21¹ located upon the type blocks and is adapted to seat against a matrix abutment 23 mounted on the upper face of the rear type block; it is held firmly in position by a matrix clamp 25 having two surfaces 25^a for coöperation with one edge and the top of the matrix and an inclined surface 25^b for coöperation with a corresponding inclined surface on the matrix abutment 23, whereby when the matrix clamp is forced down by its clamping screw 26 the matrix will be forced downwardly and against its abutment where it will be held with precision and in such relation to the type block as to prevent any liability of molten metal escaping through the joints. A squirt preventing shield 40 may, if desired, be removably held upon the clamp 25 by the washer 41 yieldingly pressed against the shield by the spring 42 positioned between the washer and the head of the screw 26.

The mold blade 27 which is mounted to reciprocate between the side blocks is of a thickness which corresponds to the point size of the material being cast and it is guided by the side blocks, and by the guide extensions 31, 32, the forward and rearward limits of its movement being determined by suitable stops, not shown. The mold blade is

provided with means whereby its operating member 35 may be readily attached thereto, such means conveniently and preferably consisting of a centrally located circular bearing into which a journal stud 36 on the end of the member 35 is adapted to work. Immediately forward of this circular bearing the mold blade is formed with an aperture 28^a preferably rectangular for the reception of a lateral rectangular projection formed on the rear end of the gate pusher 28. The projection of the gate pusher fits loosely within the aperture in the mold blade so that the pusher may without binding 10 adapt itself vertically as may be required by the guide channel 12; the parts are rectangular so that in any position a large bearing surface is provided.

The lower matrix member 21¹ rests, in the embodiment of the invention illustrated, upon the side blocks of the mold and supports upon its upper surface the upper matrix member 21. The width of the lower member is substantially the same as that of the upper member and both members are held in position by the matrix holding devices. The lower member is provided with a longitudinal slot the width of which is substantially the same as the distance between the mold side blocks, which distance represents the point size of the element being cast, and this slot, when the parts are properly positioned, is in alignment with the mold cavity formed by the said side blocks 25 so that the side walls 43 of the slot (see Fig. 4) form substantially a continuation of the mold cavity forming walls of the side blocks. The slot in this member extends short of the rear end of the latter so that there is 30 formed at said end a connection 44 (Fig. 3) integral with the sides. The end of the slot in proximity to this connection is adapted to align with the rear end of the recess 22 in the matrix member 21 when the parts are 35 positioned for operation.

The slot in the lower matrix member extends forwardly to the forward end of the said member at which point the sides thereof are connected by an integral bridge portion 45 (Fig. 3). This bridge is grooved at 46 to form a continuation of the slot, the depth of the groove being at least as great as the thickness of the main portion of the lower member added to the depth of the 50 matrix recess 22. The reason for this will be apparent upon consideration of the fact that the matrix formed portion of the element finds exit through this groove in the bridge 45 when the element after being cast 55 and congealed is pushed from the mold cavity, in a manner well understood by those skilled in the art, by the forward movement of the mold blade.

In operation the mold blade is reciprocated from a point in advance of the nozzle

opening 20 to a point in rear thereof, the top of the blade being in sliding leak-proof contact with the lower surface of the connection 44 of the lower matrix member 21¹ and molten metal is injected through said 70 nozzle opening when the blade is in its retracted position.

The forward wall of the mold cavity is not a structural part of the mold and is not shown; it is formed by the rear edge of the 75 type metal cast previously made and thereafter advanced by the forward reciprocation of the blade. At the time of casting, as will readily be understood by those familiar with the art, this previously cast type 80 metal is clamped tightly by the screw 18 in position to withstand the pressure of the entering molten metal. The bridge portion 45 of the lower matrix member is practically of importance to prevent the spreading 85 of the sides thereof because of this pressure of injected metal.

With the lower matrix member illustrated in Figs. 1, 2, 3 and 4, the slot walls 43 of which are vertical and form a vertical 90 continuation of the side block walls, a strip product is obtained, the top edge of which is provided with a V shaped projection corresponding with the groove 22 of the matrix member 21, the slanting walls extending 95 only to the top wall of the strip, a right angled shoulder being formed on each side of the projection by the meeting of the top wall and the side wall. By removing the shield 40 then unscrewing the screw 26 and 100 lifting off the clamp 25, the matrix members can be readily removed and replaced. If desired, the lower member 21¹ may be replaced by the modified lower member 21^a shown in Fig. 5 in which the slot walls 43^a 105 are slanting instead of vertical so as to form a continuation of the V shaped groove 22 in the upper matrix member. With this modified lower member a strip product is obtainable in which the slanting walls of 110 the V shaped projection extend, like those of a column rule, to the side walls of the strip body. The simple exchange of one lower matrix member for another thus makes it possible, without interference with the 115 mold proper to produce a variety of products for while but two forms are illustrated it is obvious that many other forms may be employed.

We claim—

1. A mold for elements of printing forms embodying the following instrumentalities, to-wit: blocks forming the bottom and side walls of the mold cavity, a mold blade of the same height as and working between two 125 of said blocks, an exchangeable slotted member seated upon said blocks with the slot thereof forming an extension in height of the mold cavity, an exchangeable recessed face-forming matrix member seated upon 130

4
said slotted member with the face forming recess thereof in register with the slot of said slotted member, and means for clamping both of said members in position on the 5 mold.

2. A mold for elements of printing forms embodying the following instrumentalities, to-wit: blocks forming the bottom and side walls of the mold cavity, a mold blade of 10 the same height as and working between two of said blocks, an exchangeable member seated upon said blocks and having a portion in leak-proof sliding contact with the upper surface of said mold blade, said member being provided with a slot in alinement with 15 the mold cavity to extend the height of said cavity, an exchangeable, recessed, face-forming matrix member seated upon said slotted member and having the face forming recess 20 thereof in register with the slot of said slotted member, and means for clamping both of said members in position on the mold.

3. A matrix for elements of printers' forms comprising two separable upper and 25 lower members, the upper member being provided with a face-forming recess and the lower member being provided with a slot in alinement with said recess.

4. A matrix member comprising a main

portion adapted to be located between a mold 30 and an upper matrix member, said portion being provided with a slot of substantially the point size of the mold in width and extending from the forward end of the member to a point removed from the rear end thereof, and a bridge portion at the forward end, 35 of the member connecting the sides thereof, said bridge portion being grooved in extension of the slot, the depth of said groove being greater than the thickness of said slot- 40 ted portion.

5. A matrix for strip material elements of printers' forms comprising an upper member provided with a face-forming recess in one of its surfaces, said recess extending to the 45 edge of the member, and a lower member having a main portion contacting with said surface of the upper member and provided with a slot in alinement with said recess, and a bridge portion adjacent the end of the 50 upper member, said bridge portion being provided with a groove forming an extension of said slot, said groove having a depth not less than the thickness of the main portion of the lower member added to the depth 55 of the recess in the upper member.

JOHN SELLERS BANCROFT.

AMOS L. KNIGHT.
